UNITED STATES PATENT OFFICE.

THOMAS V. ALLIS, OF BRIDGEPORT, CONNECTICUT.

METAL-HEATING FURNACE.

SPECIFICATION forming part of Letters Patent No. 729,712, dated June 2, 1903.

Application filed February 4, 1902. Serial No. 92,518. (No model.)

To all whom it may concern:

Be it known that I, THOMAS V. ALLIS, a citizen of the United States, residing at Bridgeport, in the county of Fairfield and State of Connecticut, have invented certain new and useful Improvements in Metal-Heating Furnaces, of which the following is a specification.

My invention is an improvement in metal-heating furnaces, and is particularly adapted to heat metal plates in packs, and is so constructed that regular intermittent delivery of heated metal for reduction may be maintained. With this end in view I construct a furnace preferably in the form of a hollow square. The metal is charged into the furnace at a certain point and is propelled through a rectangularly-arranged heating-chamber and delivered in a properly-heated condition at the point of entry.

To enable others to understand my invention, reference is had to the accompanying drawings, in which—

Figure 1 represents an upper plan view of the furnace with the roof removed. Fig. 2 is a detail view of the mechanism adapted to be used in squaring or evening up the plates of a pack preparatory to their being reduced, usually by rolling. Fig. 3 is a sectional view of the furnace on line *a a* of Fig. 1, with the roof added, also broken view of the chimney. Fig. 4 is a sectional view of one side of the furnace and roof on line *b b* of Fig. 3. Fig. 5 is a detail perspective view of one of the carrier-blocks with a pack of metal plates resting thereon.

The furnace is preferably in the form of a hollow square comprising the sides 1, 2, 3, and 4. The tile floor 5, Fig. 3, is supported upon the refractory stools 6. This floor extends unbroken around three sides of the furnace, terminating at *c c'*, Fig. 1, where the heating-chamber 7 (shown at Fig. 3) also terminates. 7^a is the roof of the furnace.

8 is a channel-iron resting on the furnace-floor 5. This channel-iron (see Fig. 1) extends across the opening or passage-way 9—in fact, as shown, is of unbroken construction. 10 are carrier-blocks, which are preferably cast-iron; but they may be of soap-stone or other refractory material and are mounted in said channel-irons. On these blocks are placed the metal packs 11 to be

heated. Instead of a plain upper surface, as shown, these blocks may be provided with ribs or a pocket to prevent displacement of the packs. 55

12 is a flue for the admission of fuel-gas, which gas enters the combustion-chamber 13 below the furnace-floor 5, where it is ignited. From thence the flame passes up the short flue 14, located between one edge of the floor 5 and the inner wall of the furnace, thence over said floor (see arrows) and passing off through the flues 15 as waste products of combustion (see also Fig. 3) to the chimney 16, located within the central open space 17. (Shown more clearly at Fig. 1.)

18, 19, 20, and 21 are pusher-rods located at the four corners of the furnace for the purpose of propelling the carrier-blocks with their load through the annular heating-chamber. 70

The packs or plates, as before mentioned, are entered into the furnace and delivered therefrom at the passage-way 9. In this passage-way and close to the channel-iron 8, 75 which bridges said passage-way, is situated an apparatus adapted to square or even up metal packs that are not riveted or otherwise fastened together. This apparatus (shown more clearly at Fig. 2) consists of the vertical lever 22, pivotally supported to the base 23 by pin 24.

25 is a table spanning the passage-way 9, with its ends let into the brickwork of the furnace, as shown more clearly at Fig. 1. 26 is 85 a groove in said table to permit the movement of the upper end of the lever 22. 27 is a cord or chain passing over the pulley 28 and is secured both to said lever and to the treadle 29, whereby said lever is operated, for the purpose presently to be explained.

30 is an angle-plate adjustably mounted on the table 25, whose vertical portion corresponds to the upper T-shaped end 22^a of the lever 22. 31 is a butting-block on said table, 95 and 32 is a groove in the table 25 to admit one of the jaws of a pair of tongs used for grasping the packs. 33 is a spring interposed between lever 22 and the depending lug 34 of said table to throw said lever back to its normal position. 100

When drawing a pack from the furnace whose plates are of the same size, the pack is grasped centrally by a pair of tongs and is

laid on the table 25 with the end opposite the operator and is chucked hard against the block 31, so as to even up the plates of said pack on two ends, the grip of the tongs exerting only sufficient tension to enable the plates of the pack to move for this purpose. The groove 32, as before mentioned, receives the under jaw of the tongs, so that the pack will rest on the table. The sides of the pack are then evened up between the movable lever-jaw 22 and the angular plate 30. When the pack is thus properly adjusted, it is conveyed to the reducing-machine, usually a rolling-mill. This or a similar device may be employed to even up packs before charging them onto the carrier-blocks, if desired. Each carrier-block also has the groove 10^a for the accommodation of the tongs either when entering packs into the furnace or drawing them therefrom.

The number and size of the carrier-blocks are so proportioned with respect to the size and construction of the furnace that the channel-irons 8 contain enough carrier-blocks, less one, to fill them, thus leaving a single space unoccupied. In Fig. 1 this space is represented by *d*. In operating the furnace the packs are placed on the carrier-blocks as they intermittently pass across the passage-way 9, their dwell being sufficiently long at this point for the operator to remove the hot pack and place a cold one thereon. The pusher-rod 18 is first brought into operation to propel the line of carrier-blocks on side 1 of the furnace a distance represented by the length of one carrier-block. This will bring the carrier-block at the opposite end of the line into said space *d* and leave an empty space at the corner occupied by the pusher-rod 18, which will be filled with a carrier-block through the medium of the pusher-rod 21. The pusher-rod 20 will then be operated to fill this latter space, which space will be filled by the operation of the pusher-rod 19. In this manner the carrier-blocks are charged and discharged as they are propelled in the annular heating-chambers around the furnace, and when each pack has thus traversed the furnace and arrived at the starting-point it is hot enough to be removed for reducing.

It will be understood that the heating area of the furnace is so proportioned that the predetermined intermittent movement of the packs, as above described, will bring them to the proper temperature for reducing when they have traveled once around the furnace.

The above construction of furnace, when operated in conjunction with the carrier-blocks, has marked distinctions from a previous application for a patent made by me and filed April 20, 1901, Serial No. 56,788, wherein packs are described as being progressively heated by advancing them through a heating-furnace in broken lines which are sufficiently short to prevent overriding or interlacing of the packs as they are propelled through the furnace. The packs contem-

plated in the above-named application and this are about one-half inch thick, which precludes the propulsion of any great number 70 of packs abutting each other; hence the short sections or lines of packs described in said application. By the use of the carrier-blocks, as herein described, the ends of the packs loaded on the carrier-blocks do not 75 come in contact with each other, whereby interlacing under pressure is avoided. The carrier-blocks may also be of any desired thickness, which avoids the tendency to override, as the thickness of said blocks will be 80 in proportion to the length of the line to be moved, and the arrangement of the heating-chamber in this form causes said carrier-blocks to travel in constant heat, and the blocks in their travel are loaded and unloaded 85 at a given point. It is therefore evident that the furnace may be of any continuous angular form; but that of the hollow square, herein described, is preferred as the most economical and convenient of operation. 90

I hold myself at liberty to dispense with the combustion-chamber below the work-supporting floor and carry the flame over the top of the metal, as commonly practiced.

Having thus described my invention, what 95 I claim as new, and desire to secure by Letters Patent, is—

1. A furnace for heating metal, having an endless heating-chamber, said chamber consisting of straight passages arranged at an 100 angle to each other, and means for moving metal along said passages, as set forth.

2. A furnace for heating metal, having an endless heating-chamber, said chamber consisting of straight passages arranged at an angle to each other, and means at the angular junction of each pair of passages for moving metal along one of said passages, as set forth. 105

3. A furnace for heating metal, having an endless heating-chamber, said chamber consisting of straight passages arranged at an angle to each other, an opening at the side of one of said passages for receiving and delivering metal, and means at the angular junction of each pair of straight passages for moving metal along one of said passages, as set forth. 110

4. A furnace for heating metal, having an endless heating-chamber, said chamber consisting of straight passages arranged at an angle to each other, an opening at the side of one of said passages for receiving and delivering metal, a guideway bridging said opening, and means at the angular junction of each pair of straight passages for moving 115 metal along one of said passages, as set forth. 120

5. A furnace for heating metal, having an endless heating-chamber, said chamber consisting of straight passages arranged at an angle to each other, an opening at the side of one of said passages for receiving and delivering metal, a channeled guideway bridging said opening, and means at the angular junction of each pair of straight passages for mov- 125 130

ing metal along one of said passages, as set forth.

6. A furnace for heating metal, having an endless heating-chamber, said chamber consisting of straight passages arranged at an angle to each other, an opening at the side of one of said passages for receiving and delivering metal, a guideway bridging said opening, means in said guideway for squaring the edges of packs of metal, and means at the angular junction of each pair of straight passages for moving metal along one of said passages, as set forth.

7. A furnace for heating metal, having an endless heating-chamber, a series of separate abutting carrier-blocks in said chamber, and means for moving the blocks along said chamber, as set forth.

8. A furnace for heating metal, having an
endless heating-chamber, said chamber con-
sisting of straight passages arranged at an an-
gle to each other, a series of separate carrier-
blocks in said passages, and means for mov-
ing said blocks along said passages, as set
forth.

30 9. A furnace for heating metal having an endless heating-chamber, said chamber consisting of straight passages arranged at an angle to each other, a series of separate carrier-blocks in said passages, and means at the angular junction of each pair of passages for moving the blocks along one of said passages, as set forth.

10. A furnace for heating metal, having an
endless heating-chamber, said chamber con-
sisting of straight passages arranged at an an-
gle to each other, an opening at the side of
one of said passages for receiving and deliv-
ering metal, a series of separate carrier-blocks
in said passages, and means at the angular
junction of each pair of straight passages for
moving the blocks along one of said passages,
as set forth.

11. A furnace for heating metal, having an endless heating-chamber, said chamber consisting of straight passages arranged at an angle to each other, an opening at the side of one of said passages for receiving and delivering metal, a guideway bridging said opening, a series of separate carrier-blocks in said passage, and means at the angular junction of each pair of straight passages for moving the blocks along one of said passages, as set forth.

55 12. A furnace for heating metal, having an
endless heating-chamber, said chamber con-
sisting of straight passages arranged at an an-
gle to each other, an opening at the side of
one of said passages for receiving and deliv-
60 ering metal, a channeled guideway bridging
said opening, a series of separate carrier-
blocks in said passages, and means at the an-
gular junction of each pair of straight pas-
sages for moving the blocks along one of said
65 passages, as set forth.

13. A furnace for heating metal, having an endless heating-chamber, said chamber con-

sisting of straight passages arranged at an angle to each other, an opening at the side of one of said passages for receiving and delivering metal, a guideway bridging said opening, means in said guideway for squaring the edges of packs of metal, a series of separate carrier-blocks in said passages, and means at the angular junction of each pair of straight passages for moving the blocks along one of said passages, as set forth. 75

14. A furnace for heating metal, having an endless heating-chamber, said chamber consisting of straight passages arranged at an angle to each other, and a pusher at the angular junction of each pair of passages for moving the metal along one of said passages, as set forth. 8c

15. A furnace for heating metal, having an endless heating-chamber, said chamber consisting of straight passages arranged at an angle to each other, an opening at the side of one of said passages for receiving and delivering metal, and a pusher at the angular junction of each pair of passages for moving the metal along one of said passages, as set forth. 85
90

16. A furnace for heating metal, having an endless heating-chamber, said chamber consisting of straight passages arranged at an angle to each other, an opening at the side of one of said passages for receiving and delivering metal, a guideway bridging said opening, and a pusher at the angular junction of each pair of passages for moving the metal along one of said passages, as set forth. 95 100

17. A furnace for heating metal, having an endless heating-chamber, said chamber consisting of straight passages arranged at an angle to each other, an opening at the side of one of said passages for receiving and delivering metal, a channeled guideway bridging said opening, and a pusher at the angular junction of each pair of passages for moving the metal along one of said passages, as set forth.

18. A furnace for heating metal, having an endless heating-chamber, said chamber consisting of straight passages arranged at an angle to each other, an opening at the side of one of said passages for receiving and delivering metal, a guideway bridging said opening, means in said guideway for squaring the edges of packs of metal, and a pusher at the angular junction of each pair of passages for moving the metal along one of said passages, as set forth. 115 120

19. A furnace for heating metal, having an endless heating-chamber, said chamber consisting of straight passages arranged at an angle to each other, a series of separate carrier-blocks in said passages, and a pusher at the angular junction of each pair of passages for moving the blocks along one of said passages, as set forth. 125

20. A furnace for heating metal, having an endless heating-chamber, said chamber consisting of straight passages arranged at an angle to each other, an opening at the side of

one of said passages for receiving and delivering metal, a series of separate carrier-blocks in said passages, and a pusher at the angular junction of each pair of passages for moving the blocks along one of said passages, as set forth.

21. A furnace for heating metal, having an endless heating-chamber, said chamber consisting of straight passages arranged at an angle to each other, an opening at the side of one of said passages for receiving and delivering metal, a guideway bridging said opening, a series of separate carrier-blocks in said passages, and a pusher at the angular junction of each pair of passages for moving the blocks along one of said passages, as set forth.

22. A furnace for heating metal, having an endless heating-chamber, said chamber consisting of straight passages arranged at an angle to each other, an opening at the side of one of said passages for receiving and delivering metal, a channeled guideway bridging said opening, a series of separate carrier-blocks in said passages and a pusher at the angular junction of each pair of passages for moving the blocks along one of said passages, as set forth.

23. A furnace for heating metal, having an endless heating-chamber, said chamber consisting of straight passages arranged at an angle to each other, an opening at the side of one of said passages for receiving and delivering metal, a guideway bridging said opening, means in said guideway for squaring the edges of packs of metal, a series of separate carrier-blocks in said passages, and a pusher at the angular junction of each pair of passages for moving the blocks along one of said passages, as set forth.

24. A furnace for heating metal, having an endless heating-chamber, a series of separate carrier-blocks in said chamber, each block having a groove in its upper face, and means for moving said blocks along said chamber, as set forth.

25. A furnace for heating metal, having an endless heating-chamber, said chamber consisting of straight passages arranged at an angle to each other, a series of separate carrier-blocks in said passages, each block having a groove in its upper face, and means for moving the blocks along said passages, as set forth.

26. A furnace for heating metal plates arranged in packs, having an evening device for the packs, consisting of a table carrying a butting-block and an angle-plate, and

means for pushing the pack against said angle-plate, as set forth.

27. A furnace for heating metal plates arranged in packs, having an evening device 60 for the packs, consisting of a table carrying the butting-block and an angle-plate, and a pivoted lever projecting above said table in position to push the pack against said angle-plate, as set forth.

65 28. A furnace for heating metal, having an endless heating-chamber, said chamber consisting of straight passages arranged at an angle to each other, a series of separate carrier-blocks in said passages, the length of the 70 heating-chamber and blocks and the number of blocks being such as to leave a vacant space for one block, and means at the angular junction of each pair of passages for moving metal along one of said passages, as set 75 forth.

29. A furnace for heating metal, having a heating-chamber with a work-supporting floor, a combustion-chamber beneath said floor, a series of gas-inlet ports along one side 80 of said chamber, an inlet-flue between one edge of said floor and the wall of said chamber, and a series of discharge-flues for the waste products of combustion above said floor and on the opposite side of said chamber from 85 said inlet-flue, as set forth.

30. A furnace for heating metal, having an endless heating-chamber, said chamber consisting of straight passages arranged at an angle to each other, means for moving metal 90 along said passages, a stack arranged within the inclosure surrounded by said chamber, and flues for the products of combustion leading from said chamber to said stack, as set forth.

95 31. A furnace for heating metal, having an endless heating-chamber, said chamber consisting of straight passages arranged at an angle to each other, a pusher at the angular junction of each pair of passages for moving metal along one of said passages, a stack arranged within the inclosure surrounded by said chamber, and flues for the products of combustion leading from said chamber to said stack, as set forth.

100 Signed at Bridgeport, in the county of Fairfield and State of Connecticut, this 3d day of February, A. D. 1902.
